Primary Examiner — Jennifer L Rempfer*Assistant Examiner* — Danielle Nichole Bowly(74) *Attorney, Agent, or Firm* — Oliff PLC(57) **CLAIM**

The ornamental design for a printer, as shown and described.

DESCRIPTION

FIG. 1 is a perspective view of the printer;

FIG. 2 is a front elevational view thereof;

FIG. 3 is a top plan view thereof;

FIG. 4 is a left-side elevational view thereof;

FIG. 5 is a right-side elevational view thereof;

FIG. 6 is a rear elevational view thereof; and,

FIG. 7 is a bottom plan view thereof.

The evenly spaced broken lines depict unclaimed parts of the printer and form no part of the claimed design.

1 Claim, 6 Drawing Sheets(56)
